PROTECTIVE ARRANGEMENT FOR ELECTRIC INSTALLATIONS

Application filed December 6, 1923, Serial No. 679,025, and in Germany December 14, 1922.

The present invention relates to a protective arrangement for electric installations operating in such manner as to control the opening of interrupters arranged so as to permit the separation from the installation of the parts of circuits wherein a derangement takes place. This arrangement consists substantially in the combination of a plurality of elementary relays grouped so as to form a combination of relays adapted to be considered as a multiple relay, each of which is actuated by any kind of electric action exerted thereon by the currents circulating in the installation. This action is of amperemetric character if the relay is actuated by a current the intensity of which is proportional to the intensity of the current to be controlled; it is of voltmetric character if the relay is actuated by a current the intensity of which is proportional to the tension of the current to be controlled; and it is of watt-metric character if the relay is actuated by two combined actions, one amperemetric and the other voltmetric, which gives a resultant proportional to the rate of flow of energy.

This arrangement is characterized by the combination of a plurality of elementary relays into a multiple relay, each elementary relay being actuated by any kind of electric action of the currents to be controlled, and said currents may differ from one another as to their character, phase and frequency. Said elementary relays comprise each an electric meter or measuring instrument adapted to give a mechanical action proportional to the tension or to the intensity or to the power, or to any other electric quantity of the current to be controlled, according to their winding being voltmetric or amperemetric or wattmetric; and means adapted to operate a switch interrupting said currents, when these currents, which normally must be balanced, i. e. in a predetermined ratio between each other, become unbalanced.

For this purpose there are provided means for mechanically connecting several relays with each other in such manner that when all of the currents energizing said relays are nearly balanced, that is, in a constant predetermined ratio between each other, said

means for operating the switches remain inoperative; when on the other hand, one of said currents becomes unbalanced, so that its quantity (tension, strength, power . . .) be different from that which is in said predetermined ratio with respect to the same quantity of the other currents, said means become operative and control the switch.

The invention also relates to a combination of a plurality of differential elementary relays forming a retarded operation multiple relay, with a plurality of interrupters and with means adapted to lock said interrupters when the multiple relays cause the starting of one of said control interrupters governing a circuit in which a derangement has taken place, this locking ceasing only when said latter interrupter is open.

In order to construct the device, it is necessary that the circuits to be protected be provided with interrupters adapted to open by the passage of an auxiliary current into the opening electromagnet, this current being supplied by the relay at the proper moment.

The protective device of the present invention may be used with single lines or with a group of lines terminating at the same bus bars, or with machines or with lines connected together in parallel at their two ends, and it is always formed of the same elementary device, but grouped differently according to the case.

Referring to the drawings:

Fig. 1 is a diagram of the mechanical combination of three elementary relays and a locking device.

Fig. 2 is a diagrammatic showing of three elementary relays.

Fig. 3 is a diagrammatic showing of the protective arrangement applied to three three-phase lines terminating at the same bus bars and constructed for opening the interrupters interdependently.

Fig. 4 is a diagram of three three-phase lines connected in parallel to the same bus bars, with three multiple relays for opening the interrupters when an unbalance occurs.

Fig. 5 is a diagram of three three-phase lines connected to the same bus bars operating in parallel with the current transform-

ers connected together so as to effect automatic opening during an unbalance and for a predetermined value of the total current.

Fig. 1 shows three elementary relays R_1 , R_2 and R_3 , and a locking apparatus M , connected rigidly on two supports T . The elementary relay, which is the most important device of this invention, is shown in each of the three parts of Fig. 2. The same reference characters designate the various elements in Figs. 1 and 2. The elementary relay comprises a metallic disc 11 mounted on a shaft 10 set in rotation by electro-magnet 12 and 12₁ and is subject to the action of the permanent magnet 13 as in any ordinary electric meter. The shaft 10, which rotates in supports 14, is of two parts connected together by the joint 15, which permits the upper part to be raised while allowing it to remain operatively connected with the lower part by sliding on pins 16. The lower part of shaft 10 carries at its upper end a disk 15a to which pins 16 are secured. The lower end of the upper part of shaft 10 carries a disk 15b which is provided with two holes for receiving pins 16. By this construction the two parts of the shaft are held against relative rotation, but the upper part may be moved axially with respect to the lower part. The upper part of the shaft carries an endless screw 17 whose thread has an inclination lower than the frictional angle (irreversible screw) which may rotate shaft D, by means of the toothed wheel (gear) 21 and couple 21₁ and 21₁₁, when in mesh through the action of the magnetic clutch 22. The pitch of the thread on screw 17 is such that shaft D can be rotated by revolving shaft 10, but screw 17 cannot be rotated by revolving shaft D. When the upper part of shaft 10 is raised by causes hereinafter set forth, contact c closes (Fig. 1, this is produced by raising lever 23 pivoted at 24).

There may be mounted on the same shaft 45 D two or more wheels 21₁ actuated by two or more elementary relays R_1 and R_2 etc., constructed and regulated in the same manner and traversed by currents in the same direction so as to rotate the endless screw 17 in 50 the direction for which they would cause the upper part of shaft 10 to raise if wheels 21 were stopped, and which we call the positive rotational direction; if wheels 21₁ and 21₁₁ are in mesh, shaft D rotates at a velocity 55 which is a function of the currents, and if said currents are equal, nothing else will happen; but if the two currents become unequal, more exactly, if the current which acts on R_1 becomes the stronger one, the shaft R_1 60 will have a tendency to rotate more rapidly than that of R_2 and R_3 and, through shaft D and wheels 21, will try to move screw 17 of R_2 from above downwardly; but since the pitch of this screw is almost irreversible this 65 force will have almost no effect on R_2 . Shaft

D cannot rotate at a speed greater than that which R_2 permits, and wheel 21 of R_1 connected to shaft D will rotate at this same speed (in view of the ratios of the gears being equal); therefore, when the endless screw of R_1 has a velocity greater than that of R_2 , it will appear as if wheel 21 were immovable and screw 17 of R_1 rotates with a speed equal to the difference between the actual speed of R_1 and the actual speed of R_2 , i. e., screw 17 70 moves upwardly on account of its thread revolving on teeth of wheel 21 and the upper part of shaft 10 raises and operates contact c which, completing the auxiliary circuit, 75 operates the auxiliary elements which, in turn, open the interrupter which should be opened, as set forth more clearly hereinafter. The length of endless screws 17 is such that they remain engaged with wheels 21 even when the shaft is raised. If the elementary 80 relays are traversed by currents so as to rotate in the direction opposite to that which we have discussed, that is to say in the "negative rotational direction", and so long as the currents, and their driving couples, are equal, 85 shaft D will rotate in the direction opposite that of the preceding case without operating any switch. But, if the current acting on R_1 is less than the other, the endless screw of R_1 will have a tendency to rotate more slowly 90 than that of R_2 ; shaft D, actuated by R_2 , operates wheel 21 of R_1 at a speed greater than it would have if it were merely actuated by the endless screw of R_1 ; the endless screw of R_1 which cannot, in its rotation, follow 95 the passage of the teeth of wheel 21, will be raised with the upper part of shaft 10 from R_1 , making the contact c . The same thing 100 occurs if the motor couple acting on R_1 becomes zero or changes direction.

The driving couple which electromagnets 12 exert on disc 11 and shaft 10 may be made proportional either to the tension or to the intensity or to the power of the current energizing said electromagnets. This depends on the windings of said magnets being voltmetric or amperemetric ones, or said magnets being coupled in order to give a wattmetric resultant. Said windings may, of course, be connected directly to the conductors of the electric installation one wishes to protect, or there may be provided instrument transformers, i. e., voltage and current transformers, for keeping the relays of the protecting arrangement removed from the high tension of the installations.

Where direct current is used it is necessary to add to the metallic disc 10 a suitable winding on the same shaft, the same as in direct current meters.

The operation of the elementary relays is always differential, whether the rotation of the shaft be positive or negative, and whatever may be the number of elementary relays connected to the same shaft D. The ab-

solute value of the currents which act on the elementary relays is of no importance in their operation, since this results only in a greater or lesser speed of shaft D, and this 5 value may vary from almost zero to the maximum for which the apparatus is constructed, without closing contacts c, providing that these currents remain equal to each other or in the ratio for which the apparatus is 10 constructed; in this embodiment said ratio is assumed to be 1:1 i. e., the currents to be equal.

The unbalance between the currents and thus between the couples which act on shafts 15 10 is the only cause which can produce the closure of a contact c, that is, to operate the relay. No device is provided to regulate the operation of the elementary relays relatively to the absolute value of the currents or energies which traverse them, while it is possible 20 to regulate the value of the unbalance necessary to operate the relays by acting on the weight 19 which, in Fig. 1, is placed at the end of lever 23 which is raised by the shaft 10.

25 Since the operation of an elementary relay is due solely to the variation of the ratio between the driving couple which acts on it and those which act on the other elementary relays connected to it, the different couples 30 may be the effects of causes (voltmetric, amperometric or wattmetric actions of direct or alternating currents) which differ from each other, provided they are arranged so as to vary proportionally while the working of the 35 installation remains normal.

If a plurality of elementary relays are connected on the same shaft D the operation remains the same; and so long as all the discs are acted upon by equal couples there will be 40 simple rotation of the shaft D, whether rotation of the discs be positive or negative; but if the couples change ratio, the shaft actuated by the stronger couple will be raised if rotation is positive, and the shaft actuated 45 by the weaker couple, or by that which has changed direction, if the rotation be negative. Contact c is always closed by a raising of a shaft.

The electromagnetic clutch 22 is traversed 50 by a current which acts on the elementary relay and the purpose of which is to connect mechanically shaft 10 with shaft D, by bringing together wheels 21₁ and 21₁₁ which were not meshing with each other. That is to say, 55 shafts 10 and D are operatively connected together only when the conductor to which the relay is connected is operative.

The magnetic clutch is indispensable in some cases, but superfluous in others; in the 60 latter wheels 21₁ and 21₁₁ are always in mesh.

In Fig. 1, there is mounted in the same supports T the electromagnet M (locking or blocking device) which acts on shaft H passing through all the elementary relays 65 mounted on the same supports, no matter

what the number of the relays may be; when the electromagnet is energized the sectors 25 move and act on stop members 18 carried by levers 23; if the lever is not yet raised, sector 25, coming into position above 18, prevents it from raising and prevents closure of contact c. In practice the purpose of the blocking device is to prevent other elementary 70 relays from operating while it is energized.

Three elementary relays may serve for the protection of a three-phase machine from internal injury; for example, in the case of a three-phase alternator, if it is connected in star formation, three currents taken from the proximity of the center of the star are caused to act on the three elementary relays, and if it is connected in delta, the three currents are taken from its three sides. The same applies 75 to a transformer.

In the case of an alternator the auxiliary circuit closed by the contacts c may suitably act on the excitation of the machine.

Fig. 3 is a diagram for protecting three three-phase lines connected to the same bus bars I, II, III. The device comprises nine elementary relays assembled to form three "three-phase line relays" with three shafts D and a single shaft H and a corresponding blocking device M. The same result is obtained with three shafts H and three devices 90 M with windings connected in series. In this case the magnetic clutch is useless, and the elementary relays are of the amperometric and positive rotation type. When the three lines are in normal state the three relays simply rotate (in general the three shafts D at different speeds). Assuming that by reason 95 of injury the current in conductor L''₂ becomes such that the difference between it and the two currents in L'₂ and L'''₂ is greater than the final differences between the currents of the two other groups, relay R''₂ operates to close contact c, which passes the auxiliary current from battery Ba' into electromagnet B₂ and opens interrupter A₂; the 100 blocking device prevents contacts c of relays R₁ and R₃ from closing and thus opening interrupters A₁ and A₃, so long as interrupter A₂ is not completely opened and the injured point thus isolated. The blocking device is 105 especially useful where the interrupters are controlled through timing devices to delay their operation.

The electromagnetic clutch 22 is traversed 110 by a current which acts on the elementary relay and the purpose of which is to connect mechanically shaft 10 with shaft D, by bringing together wheels 21₁ and 21₁₁ which were not meshing with each other. That is to say, 115 shafts 10 and D are operatively connected together only when the conductor to which the relay is connected is operative.

The magnetic clutch is indispensable in some cases, but superfluous in others; in the 120 latter wheels 21₁ and 21₁₁ are always in mesh.

Any slight difference between the currents of the three conductors is prevented from 125 operating the relay by the weight 19 (Fig. 1) which serves also to determine the minimum unbalance between the currents which is intended to effect the protective operation.

As has been stated, the absolute value of the currents or of the energies which traverse the conductors is of no importance, and only the unbalance between these values of 5 different conductors produces the protective operation.

If it is desired to protect electric lines connected in parallel at their two ends the elementary relays should be grouped differently.

10 Fig. 4 shows a station G from which depart three three-phase lines L_1, L_2, L_3 connected to the same bus bars I, II and III; 1, 2, 3 are the conductors which pass to the elementary relays; A^1, A^2, A^3 and B^1, B^2, B^3 respectively are the opening interrupters and electromagnets controlled by the elementary relays, either directly or through timing devices. Fig. 5 shows the station F receiving the above mentioned lines L_1, L_2, L_3 , connected 15 to the same bars; 1, 2, 3 are the conductors passing to the elementary relays; A^1, A^2, A^3 and B^1, B^2, B^3 respectively are the interrupters and electromagnets controlled by the elementary relays; the interrupters may also be 20 opened by the electromagnets K described hereinafter. The nine elementary relays which should be mounted in each station are divided into three groups, and each group may be called a "phase relay" and comprises 25 30 three elementary relays connected to three conductors (one for each line) which are of the same phase; if there are n lines in parallel each phase relay will have n elementary relays.

35 The elementary relays of the same phase are connected to the same shaft D and are subject to the action of block M and shaft H. For example, relays R'_1, R'_2 and R'_3 connected to the conductors of phase one, are 40 associated with shaft D' and controlled by a common locking magnet M' on shaft H'. Assuming that the energy flows from G to F; the elementary relays are provided with magnetic clutches and have windings of the ampere-metric type arranged for positive rotation at G, and for negative rotation at F, and are 45 connected to the conductors by current transformers T. If the three lines which connect stations G and F are in serviceable condition, and if interrupters A are closed, the three 50 currents of each phase will be equal (assuming the lines being equal; in case they were different the windings of the elementary relays would be suitably constructed) and the three elementary relays of each of the three 55 phase relays would rotate at equal speeds driving shaft D, but without operating any switch.

If, however, a ground or a short circuit occurs 60 between G and F, e. g., on wire 1 of line L_2 , energy will immediately be supplied from both systems of bus bars of station G and of station F, and great currents will flow along the grounded conductor, converging from 65 both ends of the line to the grounded point.

Consequently, in station G, the current in wire L'_2 becomes greater, since the sense of flow of current remains the same; in station F, since the sense of the short circuit current is inverted with respect to the normal current, there shall be an inversion of said current, or, at least, a reduction of it. 70

I have stated that for carrying out such a protection of a multiple feeder, the multiple relays must be arranged for positive rotation, i. e., operation through excess of current, at 75 station G and for negative rotation, i. e., operation through reduction of current, at station F. Indeed, in these conditions at station G the above-mentioned increase of current of wire L'_2 , with respect to wires L''_2 and L'''_2 , makes relay R'_2 close contacts C'_2 and operate switch A_2 of line L_2 , thus disconnecting these lines from the bus bars. At station F, where the relays rotate negatively, the above-mentioned reduction or inversion of current in wire L'_2 makes the relay R'_2 close its contacts and operate switch A_2 , thus disconnecting line L_2 from the bus bars. Now 80 the short circuit is completely isolated and the whole system becomes balanced again, while each of the unfaulty lines assumes a 85 part of the load previously carried by the disconnected line.

Generally, when such a fault on a phase 90 of a line occurs which results in an abnormal current flowing in the conductor of that phase of that line, the conductors of the same phase of the other lines become traversed by an abnormal current, although less 95 than that of the faulty line, since they are connected to the same bus bars.

In the above case, relays R'_1, R'_3 of these conductors begin to raise, like relay R'_2 , but with a lesser speed, so that contacts C'_2 become closed before relays R'_1, R'_3 have reached their upper positions. As soon as C'_2 close the tripping circuit, locking devices M become energized and prevent any further raising of relays R'_1, R'_3 . In such 100 manner, there is avoided the disconnecting of lines L_1 and L_3 on account of the transient unbalance and overload which occurs upon a fault on line L_2 , but which disappears as 105 soon as faulty line L_2 is disconnected from the bus bars.

As soon as said faulty line is disconnected, the current therein drops to zero and the magnetic clutches of the relays energized by 110 said line disconnect said relays from the common shaft D. Thus the multiple relay continues to rotate and protect the lines still connected with the bus bars and carrying currents. At the same time, locking means 115 M become de-energized and allow any relay to close contacts C; but now in general the remaining lines will be balanced; i. e., all of their conductors will carry about the same 120 current, and no relay will raise. Thus a 125 130

continuous transmission of electricity is secured.

It is obvious that disconnection of a faulty line occurs in similar manner even if 5 the fault consists in a short circuit between two wires, or in an interruption or cutting of a wire or any other fault; in all cases, the effect of a fault is an unbalance between the currents of a line, and, therefore, the relays 10 act in above-stated manner.

If one wishes to protect a system of feeders in which the energy flows sometimes in one sense and sometimes in the other, one may carry it out simply on energizing watt- 15 metrically each relay. If, for example, one has two stations G and F and three feeders L_1 , L_2 and L_3 connecting said stations and carrying current alternatively from G to F and from F to G, one may provide each of 20 said stations with a multiple relay as described above, comprising a relay energized proportionally to the rate of flow of energy in a conductor, and electromagnetic clutches for disconnecting a relay from the shaft D 25 when said relay stops, its conductor being disconnected from the system. Thus at the station supplying energy operation of the line breakers will occur on account of an excess of current in any conductor, and at 30 the receiving station on account of a drop of the received current or of a reversal of its sense of flow, what actually occurs in case of a fault protection will then be assured in any case.

The above mentioned protection may function only by reason of unbalance between the conductor currents, but not for excess load. If it is desired to open the interrupters also 35 for a predetermined load, and where current 40 transformers have been mounted for said protection, the secondaries of the transformers of the same phase may be connected in parallel through the winding of maximum relay MR, which causes all the interrupters to open 45 at the same time, by means of electromagnets K, connected in circuit with battery Ba'' . The advantage of this apparatus is that of operation for the same excess load for which it is adjusted, whatever may be the number of 50 the lines in operation.

What I claim is:

1. The combination, in an electrical power transmission system including a plurality of parallel conductors passing in groups 55 through switches, electroresponsive devices each comprising an electric meter operatively energized by one of said conductors, a shaft operatively connected with said meter and adapted to be moved by said meter at a speed 60 in direct relationship with an electric quantity of the electricity flowing in said conductor, so that said speed being compelled to vary results in a torque proportional to said quantity being applied to said shaft, a plurality of 65 said devices arranged in a group, means

adapted to connect mechanically all of the shafts of a group of said devices with each other and adapted to be moved by said shafts which rotate at speeds in a constant predetermined ratio between each other, but incapable of driving said shafts, so that a shaft tending to vary its speed results in said torque being applied to said shaft, means controlled by said shafts and adapted to operate the switches of a group of conductors when 70 the shaft of an electroresponsive device connected with a conductor of said group rotates at a speed which differs from that corresponding in the predetermined ratio to the speeds of the shafts of the other electroresponsive 75 devices of the same group, means adapted to regulate the amount of the torque exerted on said shaft by which the operation of said switches occurs.

2. The combination, in an electrical power 80 transmission system including a plurality of parallel conductors passing in groups through switches, electroresponsive devices each comprising an electric meter operatively energized by one of said conductors, a shaft operatively connected with said meter and adapted to be moved by said meter at a speed in direct relationship with an electric quantity of the electricity flowing in said conductor, so that said speed being compelled to vary 85 results in a torque proportional to said quantity being applied to said shaft, a plurality of said devices arranged in a group, means adapted to connect mechanically all of the shafts of a group of said devices with each 90 other and adapted to be moved by said shafts which rotate at speeds in a constant predetermined ratio between each other, but incapable of driving said shafts, so that a shaft tending to vary its speed results in said torque being 95 applied to said shaft, means controlled by said shafts and adapted to operate the switches of a group of conductors when the shaft of an electroresponsive device connected with a conductor of said group rotates at a 100 speed which differs from that corresponding in the predetermined ratio to the speeds of the shafts of the other electroresponsive devices of the same group, means adapted to regulate the amount of the torque exerted on said shaft 105 by which the operation of said switches occurs, means adapted to lock the electroresponsive devices against operation when one of 110 said devices has operated.

3. The combination, in an electrical power 120 transmission system including a plurality of parallel conductors passing in groups through switches, electroresponsive devices each comprising an electric meter operatively energized by one of said conductors, a shaft operatively connected with said meter and adapted to be moved by said meter at a speed in direct relationship with an electric quantity of the electricity flowing in said conductor, so that said speed being compelled 125 130

to vary results in a torque proportional to said quantity being applied to said shaft, a plurality of said devices arranged in a group, means adapted to connect mechanically all of the shafts of a group of said devices with each other and adapted to be moved by said shafts which rotate at speeds in a constant predetermined ratio between each other, but incapable of driving said shafts, so that 5 a shaft tending to vary its speed results in said torque being applied to said shaft, means controlled by said shafts and adapted to operate the switches of a group of conductors when the shaft of an electroresponsive device 10 connected with a conductor of said group rotates at a speed which differs from that corresponding in the predetermined ratio to the speed of the shafts of the other electroresponsive devices of the same group, means adapted 15 to regulate the amount of the torque exerted on said shaft by which the operation of said switches occurs, means adapted to lock the electroresponsive devices against operation when one of said devices has operated, 20 and means energized by an electric quantity of the electricity flowing in all of said conductors and arranged to operate all of said switches when said electric quantity exceeds 25 a predetermined value.

30 4. The combination, in a power supply including a plurality of parallel conductors passing by groups through switches, electroresponsive devices each comprising an electric meter energized by one of said conductors, a shaft arranged to be driven by said meter at a speed in direct relationship with an electric quantity of the electricity flowing in said conductor so that its speed being 35 compelled to vary results in a torque applied to said shaft proportional to said quantity, a plurality of said devices arranged in a group, a telescopic joint for connecting each of said meters with its shaft while permitting a raising of said shaft, a worm mounted on each of 40 said shafts, a wheel meshing with each of said worms and arranged to be driven by said worm, but incapable of driving said worm so that a shaft carrying said worm tending to 45 vary its speed results in said torque being applied to said shaft, another shaft connecting all of said wheels of said electroresponsive devices of a group with each other, and arranged to compel said wheels to rotate at 50 speeds which are in a constant predetermined ratio with each other, so that a shaft rotating at a speed which is not in said predetermined ratio with the speeds of the other shafts of the same group raises on account 55 of its worm revolving on the gear of said wheel meshing with it, a tripping relay for each of said switches having an energizing circuit, a pair of contacts in said circuit operated by 60 said device to complete said circuit when said electric quantity of the electricity

flowing in said conductor differs from a constant predetermined ratio with the same electric quantity of the electricity flowing in the other conductors energizing other devices of the same group, means to regulate the amount of the torque exerted on said first-mentioned shaft by which said raising occurs, means energized by said circuit and arranged to prevent the raising of said shafts when one of said shafts is lifted and until the switch 70 operated by it has completed its operation.

5. The combination, in a power supply including a plurality of parallel conductors passing by groups through switches, electroresponsive devices each comprising an electric 80 ampere-hour meter energized by one of said conductors, a shaft adapted to be driven by said meter at a speed proportional to the rate of flow of current in said conductor, a plurality of said devices in a group, a telescopic joint for connecting each of said meters with its shaft while permitting a raising of 85 said shaft, a worm mounted on said shaft, a wheel meshing with said worm and arranged to be driven by said worm, but incapable of driving said worm, another shaft arranged to connect all of said wheels of said electroresponsive devices of a group with each other, and arranged to compel said wheels to rotate at 90 speeds which are in a constant predetermined ratio with each other, so that a meter shaft rotating at a speed which is not in said predetermined ratio with the speeds of the other shafts raises on account of its worm revolving on the gear of said wheel meshing with it, a slow acting tripping relay for each of said switches having an energizing circuit, a pair of contacts in said circuit operated by 95 a raising of a meter shaft to complete said circuit when the flow of current in said conductor differs from a constant predetermined ratio with the flow of current in the other conductors energizing meters of the same group of devices, means to regulate the amount of said difference between the currents by which operation of said contacts occurs, means energized by said circuit and arranged to prevent the raising of said shafts when one of said shafts is lifted and until the switch 100 operated by it has completed its operation, and means energized by all of said conductors and arranged to operate all of said switches when the rate of flow of current in a conductor exceeds a predetermined value.

6. In combination, a feeder provided with 110 several conductors arranged in parallel, a switch for said feeder, electro-responsive devices each comprising an electric meter energized by one of said conductors, a shaft connected with said meter and adapted to be driven by said meter at a speed in direct relationship with an electric quantity of the 115 electricity flowing in said conductor, so that its motion being compelled to vary results in a torque proportional to said quantity being 120

125

5 applied to said shaft, said devices being arranged in a group, means adapted to connect mechanically all of the shafts of said devices with each other, and adapted to be moved by said shafts, but being incapable of driving said shafts, so that a shaft tending to vary its speed results in said torque being applied to it, means controlled by said shafts and adapted to operate said switch when the speeds 10 of said shafts differ between each other, means adapted to regulate the amount of the torque exerted on said shaft by which operation of the switch occurs and means energized by said feeder and adapted to operate said switch 15 when said electric quantity of the electricity flowing in said feeder exceeds a predetermined value.

7. In combination, a feeder provided with a number of conductors arranged in parallel, 20 a switch for said feeder, electroresponsive devices each comprising an electric meter energized by one of said conductors, a shaft arranged to be driven by said meter at a speed in direct relationship with an electric quantity 25 of the electricity flowing in said conductors, so that its speed being compelled to vary results in a torque proportional to said quantity being applied to said shaft, said devices being arranged in a group, a telescopic joint 30 for connecting each of said meters with its shaft while permitting a raising of said shaft, a worm mounted on said shaft, a wheel arranged to be driven by said worm but incapable of driving said worm, so that a shaft 35 carrying said worm tending to vary its speed results in said torque being applied to said shaft, another shaft arranged to connect all of said wheels of said electroresponsive devices with each other, and arranged to compel said wheels to rotate at speeds which are in a constant predetermined ratio with each other, so that a first mentioned shaft rotating at a speed which is not in said predetermined ratio with the speeds of the other shafts raises 40 on account of its worm revolving on the gear of said wheel meshing with it, a tripping relay for each of said switches having an energizing circuit, a pair of contacts in said circuit operated by the raising of a first mentioned shaft, and arranged to complete said circuit when said electric quantity of the electricity flowing in a conductor of said feeder differs by a predetermined amount from its normal value which is in a constant 45 predetermined ratio with the same electric quantity of the electricity flowing in the other conductors, means adapted to regulate the amount of the torque exerted on said first-mentioned shaft by which said raising occurs, 50 and means energized by said feeder and adapted to operate said switch when said electric quantity of the electricity flowing in said feeder exceeds a predetermined value.

8. In combination, a feeder provided with 55 a number of conductors arranged in parallel,

a switch for said feeder, electroresponsive devices each comprising an electric ampere-hour meter operatively energized by one of said conductors, a shaft operatively connected with said meter and adapted to be moved by said meter at a speed proportional to the rate of flow of current in said conductor, said devices being arranged in a group, a telescopic joint for connecting each of said meters with a shaft while permitting a raising of 75 said shaft, a worm mounted on said shaft, a wheel meshing with said worm and arranged to be driven by said worm, but incapable of driving said worm, another shaft arranged to connect all of said wheels of said electroresponsive devices with each other and arranged to compel said wheels to rotate at speeds which are in a constant predetermined ratio with each other, so that a first mentioned shaft rotating at a speed which is not in said 80 predetermined ratio with the speeds of the other shafts raises on account of its worm revolving on the gear of said wheel meshing with it, a tripping relay for each of said switches having an energizing circuit, a pair of contacts in said circuit operated by the raising of a first mentioned shaft and arranged to complete said circuit when the rate of flow of current in a conductor of said feeder differs for a predetermined amount 85 from its normal value which is in a constant predetermined ratio with the rate of flow of current in the other conductors, means adapted to regulate the amount of said difference between the currents by which operation of 90 said contacts occurs, and means energized by said feeder and adapted to operate said switch when the rate of flow of current in said feeder exceeds a predetermined value.

9. In combination, an electric power transmission system including a plurality of feeders each provided with a switch and each comprising a number of conductors arranged in parallel, an electroresponsive device for each conductor comprising an electric meter 100 energized by said conductor, a shaft connected with said meter and adapted to be moved by said meter at a speed in direct relationship with an electric quantity of the electricity flowing in said conductor so that its motion being compelled to vary results in a torque proportional to said quantity being applied to said shaft, a plurality of devices energized by conductors of different feeders being arranged in a group, means arranged to connect mechanically all of the shafts of said devices of a group and adapted to be driven by said shafts which rotate at speeds in a constant predetermined 110 ratio between each other, but being incapable of driving said shafts, so that a shaft tending to vary its speed results in a torque being applied to said shaft, means controlled by said shafts and adapted to operate the 115 120 125 130

switch of a feeder when the speed of the shaft of the electroresponsive device connected with a conductor of said feeder differs from said predetermined ratio with respect to the speeds of the shafts of the other devices of the same group, means adapted to regulate the amount of the torque exerted on said shaft by which the operation of the switch occurs.

- 10 occurs.

10 10. In combination, an electric power transmission system including a plurality of feeders each provided with a switch and each comprising a number of conductors arranged in parallel, an electroresponsive device for each conductor comprising an electric meter energized by said conductor, a shaft connected with said meter and adapted to be moved by said meter at a speed in direct relationship with an electric quantity of the electricity flowing in said conductor, so that its motion being compelled to vary results in a torque proportional to said quantity being applied to said shaft, a plurality of said devices energized by conductors of different 15 feeders being arranged in a group, a telescopic joint for connecting each of said meters with a shaft while permitting a raising of said shaft, a worm mounted on said shaft, a wheel meshing with said worm and arranged to be driven by said worm, but incapable of driving said worm, so that a shaft tending to vary its speed results in said torque being applied to said shaft, a shaft for each group of devices, means operatively energized by said conductor and arranged to operatively connect said second mentioned shaft with said wheel when said conductor carries an electric current, means operatively connected with said second shaft and said 20 wheels and adapted to compel said wheels to rotate at speeds in a constant predetermined ratio with each other, so that a first mentioned shaft rotating at a speed which is not in said predetermined ratio with the speeds 25 of the other shafts raises on account of its worm revolving on the gear of said wheel meshing with it, a slow acting tripping relay for each of said switches having an energizing circuit, a pair of contacts in said circuit operated by the raising of a first mentioned shaft and arranged to complete said circuit when said electric quantity of the electricity flowing in a conductor passing through said switch differs from said predetermined ratio with respect to the same electric quantity in the other conductors of the same group, means adapted to regulate the amount of the torque exerted on said first 30 mentioned shaft by which said raising occurs, means arranged to prevent the raising of said shafts when one of said shafts is lifted and until the switch operated by it has completed its operation, and means energized by all of said conductors and arranged 35 to operate all of said switches when said 40 45 50 55 60 65

electric quantity exceeds a predetermined value.

11. The combination, in an electric power transmission system including a plurality of feeders each provided with a switch and each comprising a number of conductors arranged in parallel, an electroresponsive device for each conductor comprising an electric amper-hour meter energized by said conductor, a shaft connected with said meter and adapted to be moved by said meter at a speed proportional to the rate of flow of current in said conductor, a plurality of said devices energized by conductors of different feeders being arranged in a group, a telescopic joint for connecting each of said meters with a shaft while permitting a raising of said shaft, a worm mounted on said shaft, a wheel meshing with said worm and arranged to be driven by said worm, but incapable of driving said worm, another shaft for each group of devices, means operated by the current flowing in said conductors to connect said second mentioned shaft with a wheel when the rate of flow of current in said conductors exceeds a predetermined amount, means connecting said second shaft and said wheels and adapted to compel said wheels to rotate at speeds in a constant predetermined ratio with each other, so that a first mentioned shaft rotating at a speed which is not in said predetermined ratio with the speeds of the other shafts raises on account of its worm revolving on the gear of said wheel meshing with it, a slow acting tripping relay for each of said switches including an energizing circuit, a pair of contacts in said circuit operated by the raising of a first mentioned shaft electromechanically connected with a conductor passing through said switch, and arranged to complete said circuit when the rate of flow of current in said conductor differs by a predetermined amount from a constant predetermined ratio with respect to the rate of flow of current in the other conductors of the same group, means adapted to regulate the amount of said difference between the currents by which operation of said contacts occurs, means energized by said circuit and arranged to prevent the raising of said shafts when one of said shafts is lifted and until the switch operated by it has completed its operation, and means energized by all of said conductors and arranged to operate all of said switches when the rate of flow of current in a conductor exceeds a predetermined value.

In testimony whereof I affix my signature.
UMBERTO MODIGLIANI.
